DRY SHAVER CASING

Adam Koronczi, Klagenfurt, Austria, assignor to Carinthia Elektrogerate Gesellschaft m.b.H., Klagenfurt, Carinthia, Austria

Original design application Mar. 9, 1966, Ser. No. 1,375, now Patent No. 207,944, dated June 13, 1967. Divided and this application May 4, 1967, Ser. No. 9,023

Claims priority, application Austria Sept. 9, 1965

Term of patent 14 years

(Cl. D95—3)

FIG. 1 is a side elevation of the shaver casing showing my new design,

FIG. 2 is an end elevation thereof,

FIG. 3 is a top view thereof, and

FIG. 4 is a perspective view thereof.

This is a division of design application Ser. No. 1,375, filed Mar. 9, 1966, and now Patent No. 207,944.

I claim:

The ornamental design for a dry shaver casing, as shown and described.
